UNITED STATES PATENT OFFICE.

JOHN L. FRUIN, OF CHICAGO, ILLINOIS; ROBERT E. FRUIN EXECUTOR OF THE SAID
JOHN L. FRUIN, DECEASED.

DRAINAGE AND VENT FITTING FOR PLUMBING SYSTEMS.

Application filed September 21, 1922. Serial No. 589,603.

To all whom it may concern:

Be it known that I, JOHN L. FRUIN, a citizen of the United States, residing at Chicago, in the county of Cook and State of Illinois, have invented certain new and useful Improvements in Drainage and Vent Fittings for Plumbing Systems, of which the following is a specification.

This invention relates in part to an improved plumbing system designed to handle the discharge from a closet, bathtub, lavatory or sink in a multiple story building; and the main object of the invention is to provide special drainage and vent fittings at the top and intermediate floors of such a character and structure as to permit the main soil and vent stack and the revent stack to lie in close juxtaposition and occupy but a minimum of space in a vertical wall of the building in which the system is installed.

Other objects and attendant advantages of the invention will be apparent to persons skilled in the art as the same becomes better understood by reference to the following detailed description, taken in connection with the accompanying drawing, in which—

Fig. 1 is an elevation of my improved plumbing system installed in a manner to receive the discharge from a closet or bath-tub;

Fig. 2 is a similar view of the same system, installed in a manner to accommodate the discharge from a lavatory or sink;

Fig. 3 is an elevation in a plane at right angles to that of Figs. 1 and 2 of the top-most drainage and vent fitting;

Fig. 4 is a similar view of the drainage and vent fitting used at intermediate floors; and

Fig. 5 is a cross-section on the line 5—5 of Fig. 1.

Referring to the drawing, 1 designates the lower floor, 2 an intermediate floor, 3 a top floor, and 4 a roof of a multiple story building such as is adapted to be served by my improved plumbing system.

Referring first to Fig. 1, the main vertical soil and vent stack comprises an upper straight pipe section 5 extending through the roof 4, the main stem 6 of a drain and vent fitting located at the top floor 3 and connected at its upper end into the pipe section 5, an intermediate straight pipe section 7 connected into the lower end of the main stem of the fitting 6, a main stem 8 of an in-

termediate drain and vent fitting located at the intermediate floor 2 and connected into the lower end of the pipe section 7, another straight pipe section 9 connected at its upper end to the lower end of the stem 8 of the intermediate fitting, the arm 10 of a lower fitting located at the first floor 1, and the lower portion of the main stem 11 of said lower fitting, this latter connecting into the house drain indicated at 12.

The revent stack comprises an elbow branch 13 of the top fitting, a straight vertical pipe section 14 communicating with the lower end of the elbow branch 13, a curved or bent section 15 communicating with the lower end of the vertical straight section 14, and a lower straight section 16 communicating at its upper end with the bent section 15 and at its lower end with the upper end of the main stem 11 of the lowermost fitting.

The upper fitting is provided with a lateral drain branch 17 disposed below the junction of the members 6 and 13; the intermediate fitting has an arm 18 on which is a lateral drainage branch 19, and the lower fitting is equipped with a lateral drainage branch 20 located above the junction of the main stem 11 and arm 10.

At the intermediate floor is a vertical branch 21 of the revent stack that extends from the junction of the sections 14 and 15 straight downwardly into the upper end of the fitting arm 18 to provide a vent for the drainage branch 19.

It will be observed that in the described construction the vertical soil and vent stack and the revent stack lie very close together and substantially contiguous, and that the reventing of all the fixtures below the top and next to the top floors is secured by including in the revent stack the laterally offset curved or bent section 15 at each intermediate floor by which the revent conduit is carried past the drainage branch 19 at each intermediate floor. I have herein shown but a single intermediate floor; but it will be understood that where there are several intermediate floors, the structure and arrangement herein shown at the intermediate floor 2 will simply be repeated at all the other intermediate floors.

The compact system above described may, so far as the general organization is concerned, be built up from suitable pipe sections and fittings as desired; but a consider-

able economy in the number of parts required can be effected by employing the novel integral fittings shown at the top and intermediate floors; the stem 6, elbow vent branch 13, and drainage branch 17 of the upper fitting being made integral; and the main and branch drain elements 8, 18 and 19 and the main and branch vent elements 15 and 21 of the intermediate fitting being all 10 made integral. By employing the integral fittings herein shown and described, the entire system can be assembled with the addition of ordinary straight pipe sections such as 5, 7, 9, 14 and 16.

15 With the system installed in the relation to the floors shown in Fig. 1, the drainage branches 17, 19 and 20 are adapted to serve either a closet or bathtub. In Fig. 2 I have illustrated the arrangement of the system in 20 relation to the floor levels that will be employed where the drainage branches 17, 19 and 20 serve a lavatory or sink. The structural organization of the system shown in Fig. 2 is identical with that shown in Fig. 1.

25 I claim—

1. A one-piece intermediate drainage and vent fitting for plumbing systems, comprising a vertical limb adapted to form part of a waste and vent stack and having a straight upwardly inclined lateral arm, a second vertical limb parallel with said first-named limb and continuous at its lower end with said arm and having a venting function, a lateral drainage branch on said arm 30 and a third limb merged at its upper end

into said second vertical limb and extending downwardly and inwardly beneath said arm, said third limb lying in the plane of said vertical limbs and adapted to form part of a revent stack.

2. A one-piece intermediate drainage and vent fitting for plumbing systems, comprising a vertical limb adapted to form part of a waste and vent stack and having a straight upwardly inclined lateral arm, a second vertical limb parallel with said first-named limb in close proximity thereto and merged at its lower end into the upper end of said arm and having a venting function, a lateral drainage branch on said arm and a third limb disposed alongside, and in the plane, of said vertical limbs, said third limb merged by an elbow bend at its upper end into said second vertical limb adjacent to the upper end of the latter and at its lower end inclined downwardly and inwardly beneath said arm, said third limb adapted to form part of a revent stack.

3. A one-piece top drainage and vent fitting for plumbing systems, comprising a vertical limb adapted to form part of a waste and vent stack, a depending elbow branch on the upper end of said vertical limb adapted to form the upper end of a revent stack, and a lateral drainage branch on 60 said vertical limb below the junction of the latter and said depending elbow branch, and extending in a vertical plane at an angle to the vertical plane of said elbow branch.

JOHN L. FRUIN.
